UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A LAMP-FOUNT HOLDER.

SPECIFICATION forming part of Design No. 20,866, dated June 30, 1891.

Application filed June 1, 1891. Serial No. 394,762. Term of patent 14 years.

To all whom it may concern:

Be it known that I, ALBERT PATITZ, of Meriden, in the county of New Haven and State of Connecticut, have invented a new Design for 5 a Lamp-Fount Holder, (Case C;) and I do hereby declare the following, when taken in connection with accompanying drawing and the letters of reference marked thereon, to be a full, clear, and exact description of the same, 10 and which said drawing constitutes part of this specification and represents a perspective view of the holder.

This invention relates to a design for that 15 part of a standard lamp which supports or incloses the removable fount, commonly called the "fount-holder;" and the design consists in the configuration and ornamentation of the holder, as shown in the accompanying illustration.

20 The holder is in outline of spherical shape, or starting from the bottom expands by an

outward curve, the curve turning inward toward the top, and the surface of the holder is ornamented by the representation of panels, the central portion of which is of circular 25 shape with a semicircular projection at the top and bottom. Between the two panels is the representation of a cherub with the arms resting on a panel at the respective sides, as shown in the accompanying illustration. 30

I claim—

The design for a lamp-fount holder, as herein described, and shown in the accompanying illustration.

In testimony whereof I have signed this 35 specification in the presence of two subscribing witnesses.

ALBERT PATITZ.
